UNITED STATES PATENT OFFICE.

MAGDALENA DIENER AND CHARLES FREDOLIN URBAN, OF MILWAUKEE, WISCONSIN.

VENTILATED HAT.

1,170,052.

Specification of Letters Patent.

Patented Feb. 1, 1916.

Application filed April 8, 1912. Serial No. 689,427.

To all whom it may concern:

Be it known that we, MAGDALENA DIENER and CHARLES FREDOLIN URBAN, citizens of the United States, both residents of the city of Milwaukee, county of Milwaukee, and States of Wisconsin, have invented a new and useful Improvement in Ventilated Hats, of which the following is a specification.

10 One of the main objects of our invention is to provide more efficient ventilation for a hat of the derby type, or in short, any man's hat, and, incidentally, to conceal and render inconspicuous these ventilating features, and to construct the hat-band so as to afford a better hold for the hat on the head. To obtain these results we have devised certain novel and useful features which are hereinafter fully set forth, said features 15 also incidentally producing other beneficial results as will appear.

In the accompanying drawings constituting a part of this specification: Figure 1 is a perspective view of a hat embodying our 20 improvement, certain portions being broken away to disclose otherwise concealed parts; Fig. 2 is a partial section taken approximately on the line 2—2 of Fig. 1, looking toward the right; Fig. 3 is a perspective 25 view showing a part of the skeleton band which encircles the crown of the hat; Fig. 4 is a perspective view showing a part of the fluted sweat-band used in our improvement; and Fig. 5 is an elevation of a fragmentary 30 part of the hat body, showing the perforations provided in the same.

a represents the body of a hat of any convenient type. It is provided with a plurality of perforations as *b* at the brim, as 40 shown in Figs. 1 and 5. A skeleton band, *c*, is secured on the exterior of the hat body at the brim, and this skeleton band is covered by a hat band, *d*, of the usual type. On the interior of the hat, at the brim, is affixed a 45 fluted sweat-band, the flutes extending vertically and preferably being so tapered that their largest diameter will be at the base of the band. The obvious result of such construction is to incorporate more material at 50 the base than at the top of the sweat-band. This provides a soft surface, at the bottom part of the sweat-band, for comfortably holding the hat on the head, but prevents undue pressure, which is liable to affect the

nerves and veins here located. It also causes 55 the top part of the sweat-band to recede more abruptly from the head, and in so doing provides a better ventilation space, keeping the top of the head dry. The described arrangement of the fluted sweat 60 band also provides for an unobstructed passage of air at the interior and brim of our hat. Said construction, incidentally, will also cause the hat to set more securely on the head, for the hold of the sweat-band on 65 the head will be more effective. The air admitted through the fluted sweat-band passes through the exterior hat-band, and consequently the latter must be made of fabric having coarse or fine mesh, accord- 70 ing to the degree of ventilation desired. By spacing the hat-band from the body of the hat, by means of the skeleton band *c*, as described, a proper ventilation is assured.

The sweat-band is preferably constructed 75 of thick but soft material, preferably pliable leather, since any hard material is objectionable in devices of this kind. The softness and pliability of the sweat-band equalizes the pressure of the hat on the head 80 and renders it very comfortable to the wearer.

The perforations, *b*, at the brim of the hat, will only be covered in minor part by the skeleton band *c*, and hence the passage 85 of air therethrough will not be obstructed. The fluted sweat-band is also perforated, as indicated by *g*. The skeleton band, *c*, is made of thin material, so as to be concealed by the hat band *d*, thus rendering this part 90 of our hat inconspicuous, in fact practically invisible, so that it will not attract attention to the wearer of our improved hats.

We claim:

1. The combination in a hat of a crown 95 having a wide section of coarse perforations extending all around the circumference and adjacent the brim, an interior sweat band made of pliable perforated material formed with vertically disposed flutes spaced apart 100 and extending all around the sides of the crown, a skeleton spacer band affixed exterior of the perforations of the crown, and a hat band of coarse mesh concealing said skeleton spacer band. 105

2. The combination in a hat of a crown having a wide section of coarse perforations extending all around the circumference and

adjacent the brim, an interior sweat band made of pliable perforated material formed with vertically disposed flutes spaced apart and extending all around the sides of the crown, and of greater cross section at the bottom than at the top, a skeleton spacer band affixed exterior of the perforations of

the crown, and a hat band of coarse mesh concealing said skeleton spacer band.

MAGDALENA DIENER.

CHARLES FREDOLIN URBAN.
